UNITED STATES PATENT OFFICE.

KNUTE BERGER, OF SEATTLE, WASHINGTON, ASSIGNOR TO WASHINGTON IRON WORKS, OF SEATTLE, WASHINGTON, A CORPORATION OF WASHINGTON.

CABLEWAY-CARRIAGE.

1,383,782.

Specification of Letters Patent.

Patented July 5, 1921.

Application filed June 1, 1920. Serial No. 385,589.

To all whom it may concern:

Be it known that I, KNUTE BERGER, a subject of the King of Norway, and resident of the city of Seattle, in the county of King and 5 State of Washington, have invented certain new and useful Improvements in Cableway-Carriages, of which the following is a specification.

My invention relates to cableway carriages and consists of certain constructions whereby the fall line used in connection with the carriage may be locked so as to hold the load suspended by the fall rope, without having to depend upon the strain applied to the fall rope by the engine, and whereby also the fall-line-locking mechanism may be released when it is desired to lower the fall block.

The features of my invention which I 20 deem to be novel will be described in connection with associated parts of a carriage and the parts which I believe to be novel and upon which I desire to secure a patent will then be defined by the claims.

25 In the accompanying drawings I have shown my invention embodied in the features of the construction which I prefer to use.

Figure 1 is a side view of a carriage having my invention embodied therein.

Fig. 2 is a section taken on the central plane of the carriage.

Figs. 3 and 4 are, respectively, side view and central sectional view of a carriage 35 showing a slight modification in the type of locking mechanisms.

Figs. 5 and 6 are similar views showing another slightly modified form of construction.

40 Fig. 7 is a view showing the type of cableway with which my device is intended to be used.

The chief purpose of my invention is to make it possible to raise the fall block to, 45 or partly to, the carriage and then to hold it locked in that position while the carriage is moved along the trackway or standing line. The carriage as shown in the drawings consists of a frame composed of two plates 1, 50 these plates being separated sufficiently to accommodate the sheaves and locking mechanism which are employed. This carriage has the usual track wheels 10, which run

upon the main or standing cable 11, the latter cable forming the track and supporting means for the carriage.

The carriage has a sheave, as 3, over which the fall line 30 passes. This fall line has a fall block 31 mounted in a loop thereof, the end of the fall line extending back to and 60 being supported from the carriage. A section of this fall line adjacent to the carriage is preferably made as a chain, as a chain acts better with my locking mechanism than would a cable.

65 The locking mechanism for the fall line consists of two parts, one of which, at least, is movable relative to the other and between which the fall line passes. In Fig. 2 one of these holding mechanisms consists of a 70 block 4 which is fixed between the side plates 1 of the carriage. The other or complementary holding member consists of a bell crank or two-armed lever 5 which is pivoted at 50 between the side plates of the 75 carriage. The arm 51 is of such length as to extend over to and engage the fall line opposite the face of the block 4. In the position of these parts shown in Fig. 2, it is evident that the fall line will be held so that 80 the fall block 31 cannot lower, whether or not a strain is placed upon the fall line beyond the holding dog.

The fall line 30 passes about the fall block 31 and has its end extending upwardly and 85 secured to the arm 51 which engages with and holds the fall line. To the other arm 52 is secured a line 6, by which the dog is controlled. This line 6 extends in the opposite direction from the carriage from that of the 90 fall line. It may be the back haul line or its equivalent.

In some cases, and preferably in most cases, a second pulley 40 is mounted between the sides of the carriage below the pulley 3, 95 over which the fall line passes. This serves as a guide for the fall line.

In Fig. 3 I have shown lever arms 7 and 70 which are connected, as by link 71, so as to move together and which are in turn secured to the shafts of the movable locking dogs 53 and 54. The dog 54 is shown as movable and acts as a substitute for the fixed block 4. These blocks as shown are grooved to accommodate the chain and hold the 105 chain by positive gripping against the sides

thereof, whereas the dog 51 as shown in Fig. 2, engages under the end of one of the links to thereby hold the chain.

In Fig. 6 a modified construction is shown 5 in which the holding is done after the same plan as shown in Fig. 2, but in which a supplemental holding dog 55 is substituted for the fixed block 4.

I prefer to provide both arms of the movable locking dog 5 with more than one hole, 10 as 8, for the purpose of attaching the fall line and the back haul line thereto, so that the relative strength of action of the two lines upon this dog may be varied and controlled.

This mechanism provides automatically locking means for holding the load after it has been raised by the fall line. The usual carriage hauling lines may be employed in 20 addition to those described, in which case the line 6 becomes merely a lock controlling line.

It will be noted that in the locked position the end of the fall line 30 being secured 25 to the two-armed lever 5, between the thrust block 4 and the pivot 50 of the lever, there is a certain downward moment due to the weight upon the fall block 31. To release the lock upon the fall line, the locking arm 30 of the lever is raised and this action draws the connection of the fall line thereto inward toward its pivot, with reference to a horizontal line through the pivot. This results in decreasing the downward movement upon 35 the fall line and if the connection of the fall line to the lever is brought vertically above its pivot 50, the downward moment is reduced to zero. This permits the locking lever to remain open when the haul back line 40 6 is slackened and permits the fall line 30 to be slackened to lower block. If the downward moment upon the lever 5 were not thus decreased its tendency would be always to lock as soon as there were any slack in 45 the system. With the construction described, in practice it will only lock when there is a material increase in the weight upon the fall block 31, as when a log is attached thereto. When this occurs the extra 50 weight will draw the locking arm 51 into locking position and the slackening of the fall line 30 will be immediately locked.

What I claim as my invention is:

1. A fall line grip for cableway carriages 55 comprising a hinged gripping member adapted to engage the fall line, the fall line forming a loop and having its end connected to said gripping member to hold it in gripping position, and means for releasing the

grip, mounted upon the carriage and connected with the back-haul line to be actuated thereby.

2. A fall line gripping device for cableway carriages comprising a thrust block, a two armed lever pivoted within the carriage, 65 one arm of said lever being opposite said thrust block and adapted to engage the fall line, means for securing the end of the fall line to the said arm of the lever, to hold it in gripping position, and means for securing 70 the back haul line to the other arm of the lever to release the grip.

3. In a fall rope carriage, in combination, 75 a fall line guide, a fall line, a fall block within a loop of the line, a fall line holding dog pivoted in the carriage, a thrust and dogging member complementary to the holding dog, the end of the fall line being secured to the dog to hold it in line-holding position, a back haul line, the dog having 80 an arm to which the back haul line is secured whereby the dog may be relieved to free the fall line.

4. The combination with a cableway carriage of a fall line sheave, opposed line gripping members between which the fall line passes from said sheave, said gripping members having relative movement toward and from each other in gripping and releasing 85 the fall line, the fall line end being secured 90 to a movable member of the gripping device, and a back haul line secured to the same movable member of the grip and acting in opposition to the fall line thereon.

5. A cableway carriage comprising side 95 frames, trackway sheaves journaled therein, a fall line, a fall line sheave, a two armed line-gripping member pivoted in the frame and adapted to engage one arm with the fall line after it passes over its sheave, the end 100 of the fall line being secured to the same arm and by its downward pull acting to hold the gripping member in engagement with the line, and a back haul line secured to the other arm of said gripping member to release the 105 line.

6. In a fall line gripping device for cableways, a pivoted lever having an arm adapted to grip the fall line as said arm approaches a horizontal position, the fall line forming a loop and having its end connected to the said gripping arm of the lever, and means actuated by the back haul for raising the gripping arm of the lever to release the fall line.

Signed at Seattle, Washington, this 25th 115 day of May 1920.

KNUTE BERGER.
